Patented Aug. 2, 1955

175,245

DISH RACK

Antonio Bertone, Houston, Tex.

Application April 6, 1954, Serial No. 29,881

Term of patent 14 years

(Cl. D44—29)

A cup and plates are shown in broken lines for purposes of illustration.

I claim:

The ornamental design for a dish rack, as shown and described.
